DESIGN FOR A CORNER PIECE

Henry F. Lange, Cleveland, Ohio

Application April 30, 1947, Serial No. 138,710

Term of patent 7 years

(Cl. D18—2)

To all whom it may concern:

Be it known that I, Henry F. Lange, a citizen of the United States, residing at Cleveland, in the county of Cuyahoga and State of Ohio, have invented a new, original, and ornamental Design for a Corner Piece, of which the following is a specification, reference being had to the accompanying drawing, forming part thereof.

In the drawing, the single view is a perspective of a corner piece, showing my new design.

I claim:

The ornamental design for a corner piece, as shown.

HENRY F. LANGE.
